CLAIM

We claim the ornamental design for a tobacco box, as shown and described.

DESCRIPTION

FIG. 1 perspective view of a tobacco box showing our new design;

FIG. 2 is a top plan view thereof;

FIG. 3 is a bottom plan view thereof; and,

FIG. 4 is a side elevation view thereof.

The broken lines immediately adjacent to the shaded areas represent the bounds of the claim. Only the surfaces with applied surface shading are included in the claimed design. Those surface areas with no surface shading and the broken lines illustrate the portions of the design that form no part of the claim.
